TOY MACHINE PISTOL

Mahlon E. Hirsch, Fairview, Pa., assignor to Louis Marx
& Co., Inc., New York, N.Y., a corporation of New
York

Filed Feb. 11, 1966, Ser. No. 1,013

Term of patent 14 years

(Cl. D34—15)

FIG. 1

FIG. 2

FIG. 3

FIG. 4

FIG. 5

FIG. 6

FIG. 1 is a top view of a toy machine pistol embodying my new design;

FIG. 2 is a side elevational view thereof;

FIG. 3 is a bottom view thereof;

FIG. 4 is a view similar to FIG. 2, showing the opposite side thereof;

FIG. 5 is a front end view thereof; and

FIG. 6 is a rear end view thereof.

I claim:

The ornamental design for a toy machine pistol, as shown.
